FUSE LINK CONSTRUCTION

Alwin G. Steinmayer, Milwaukee, Wis., assignor
to Line Material Company, South Milwaukee,
Wis., a corporation of Delaware

Application May 3, 1935, Serial No. 19,670

10 Claims. (Cl. 200—135)

This invention relates to improvements in fuse links.

Heretofore it has been the practice to provide in tensioned fuse links a fusible section comprising a fuse wire of low melting point and low tensile strength and also a strain wire adjacent the fuse wire and of high melting point and high tensile strength for the purpose of assuming all of the tensile load and relieving the fuse wire of all 10 of such tensile load. As a result, the fusible section of the fuse link was comparatively weak in torsional strength and the fuse wire would be frequently broken, if not seriously damaged, before the fuse link was placed in a fuse cartridge. 15 Not only is a fuse link constructed with a fuse wire and a strain wire parallel thereto inherently weak torsionally, but such links frequently become so badly twisted that the fuse wire and strain wire are brought into intimate contact with 20 each other, thereby changing the calibration of the link from that which is based upon a link in which the wires are separated from each other. Furthermore, it has been found that the calibration of a link of this type varies with any change 25 in distance between the fuse wire and strain wire even though these wires may not be in contact with each other. Even with the most careful handling, it is found that the calibration of such fuse links varies between the time they are manufactured and the time they are actually placed in 30 operation. Therefore, it is the principal object of this invention to provide a fuse link which has a fusible section embodying the equivalent qualities of a fuse wire and a strain wire parallel thereto and which will not have the defects above noted.

Re-stated, the principal object of this invention is to provide for a tensioned fuse link, a fusible section which will retain all of the tensile 40 strength and fusing qualities of the fuse links previously noted, but which will have in addition thereto greater torsional strength, greater flexing strength, greater heat concentration at the fusible section, and more accurate calibration for 45 fusing purposes.

More specifically it is an object of this invention to provide for tensioned fuse links a fusible section in which the tension wire and the fuse wire are concentrically disposed, thus increasing 50 the torsional and the flexing strength of the fusible section, securing more accurate calibration of the fusing qualities of the fusible section, and securing a greater concentration of heat on the fuse wire than has heretofore been possible.

55 A further object of this invention is to pro-

vide a fuse link having a fusible portion terminating at one end in an enlarged cross-sectional area adapted to serve as a support for a tube of insulation surrounding the fusible section of the fuse link thereby increasing the rapidity with which pressure is built up in the arcing space and cause a more rapid extinction of the arc, and to provide at the other end of the fusible section an enlarged end having a cross-sectional area less than the diameter of the tube and 10 against which the pressure above referred to will exert itself to expel the free fuse section from the tube and further shorten the time during which an arc will exist.

Other and more limited objects will become 15 apparent as the description of this invention proceeds.

In the drawing:

Fig. 1 is a view in side elevation of a fuse link embodying this invention, a portion of the tube 20 being broken away.

Fig. 2 is an enlarged fragmentary view of the fusible portion of the fuse link shown in Fig. 1, the fusible portion being in vertical section.

Fig. 3 is a view similar to that shown in Fig. 25 2, but taken at 90° relative thereto, the fusible portion being illustrated in dotted lines.

Fig. 4 is an enlarged sectional view taken on the line 4—4 of Fig. 1.

Fig. 5 is an enlarged sectional view taken on 30 the line 5—5 of Fig. 1.

Throughout the several views like parts are identified by the same reference characters.

The fuse link illustrated in the drawing comprises a terminal head 1, a flat substantially rigid 35 terminal section 2, a flexible terminal section 3, and a fusible section 4, connecting the flat substantially rigid terminal section and the flexible terminal section.

The fusible section 4 includes a strain wire 5 having its upper end looped through the aperture 17 in the terminal section 2 and its lower end looped through the aperture 7 in the rigid portion 8 of the flexible section. The ends of the strain wire are twisted about the intermediate portion 45 of the wire after they have been passed through the apertures as indicated. This strain wire has a relatively high tensile strength and a relatively high melting point.

As clearly illustrated in Fig. 2, the strain wire 50 is encased in a metallic sheathing 6 having a relatively low melting point and a relatively low tensile strength. This sheathing terminates at the upper end in an enlarged knob 9 having a cross-sectional area greater than the intermediate por- 55

tion of the sheathing 6 and embedding the upper looped and twisted end 10 to securely anchor the strain wire 5 relative to the terminal section 2. The lower end of the sheathing 6 terminates in an enlarged knob 11 which embeds the lower looped and twisted end 12 of the strain wire 5 to securely hold the strain wire rigid relative to the rigid end 8 of the flexible section 3. The knob 11 has a cross-sectional area greater than the 10 cross-sectional area of the intermediate portion of the sheathing 6, but the cross-sectional area of the knob 11 is less than the cross-sectional area of the knob 9 at the upper end of the sheathing. As clearly illustrated in Figs. 2, 3, and 4, the terminal section 2 is provided at its lower end with a tongue 13 which is entirely embedded in the knob 9, the knob 9 being substantially the same in dimension as the terminal section is in width. A second aperture 14 is shown in the terminal section 2. This aperture 14 permits the metal composing the knob 9 to unite at the upper end of the knob and thus give greater strength to the union between the knob and the terminal 2. As shown in Fig. 1, the terminal section 2 is provided with 25 a notch 15. This notch is provided so that the terminal head 1 may be broken off of the terminal section 2 when it is desired to adapt the fuse link to certain cartridges which will not receive the terminal head 1.

30 In Fig. 1 a tube 16 surrounds the fusible portion 4 and a portion of the flexible section 3. This tube is composed of insulating material, such as fibre, and snugly engages the knob 9 to be supported thereby. As shown, the knob 11 is 35 smaller in dimension than the inner diameter of the tube 16. Thus, when the fusible portion 4 is severed the remaining lower portion of the link within the tube may freely move to the open end of the tube.

40 The tube 16 serves a twofold purpose, namely, as a protecting element for the fusible portion 4 whenever the fuse link is handled prior to its insertion in a fuse cartridge and also as a means of building up a pressure in the arcing area, tending 45 to extinguish an arc and to force the severed sections of the fuse link apart more rapidly than they would otherwise tend to separate if the tube 16 were not provided.

When the fuse link is formed, the fusible portion 4 is cast about the strain wire 5 to form an 50 intimate bond or union between the strain wire 5 and the sheathing 6 as well as between the sheathing and the terminal 2 and rigid section 8. It has been found that this construction makes 55 a comparatively rigid fusible portion which has greater torsional strength than has heretofore been possible in fuses of like rating. It is found also that this construction makes a fusible section, which has considerable resistance, to bending 60 stresses, which will not change its calibrated rating before being placed in operation and which will concentrate the greater portion of the heat generated by an overload upon the fusible portion and consequently permit a much more accurate 65 calibration of the fusible portion than has heretofore been possible in tensioned fuse links.

It has also been found that the cost of manufacturing a fuse link as indicated, is less than the cost of manufacturing tensioned fuse links 70 heretofore provided and also that the product is more uniformly consistent. It has also been found that the product can be delivered to customers in far better condition than has heretofore been possible with fuse links of the type 75 noted in the statement of objects.

I claim:

1. A fuse link having spaced terminal sections each provided with a transverse aperture, a strain wire connecting said sections and having its ends looped through said apertures and twisted upon the intermediate portion of the wire, and a fusible portion having a relatively low melting point and connecting the terminal sections, said fusible portion encasing all portions of the strain wire. 5

2. A fuse link comprising spaced terminal sections, a strain wire connecting said sections, and a low melting encasement surrounding the strain wire and connecting the terminal sections, the ends of the encasement being larger in cross-sectional area than the intermediate portion of the encasement and one of said ends being larger in cross-sectional area than the other of said ends; in combination with a tube of insulation surrounding said encasement and snugly engaging the larger of said ends. 10

15 3. A fuse link comprising spaced terminal sections, a strain wire connecting said sections, and a low melting encasement surrounding the strain wire and connecting the terminal sections, the ends of the encasement being larger in cross-sectional area than the intermediate portion of the encasement; in combination with a tube of insulation surrounding said encasement and snugly engaging one of said ends. 20

30 4. A fuse link comprising an upper terminal section, a lower terminal section, a strain wire connecting said sections, and a low melting encasement surrounding the strain wire and connecting the terminal sections, the ends of the encasement being larger in diameter than the intermediate portion thereof and the end connected with the upper terminal section being larger in diameter than the diameter of the lower terminal section; in combination with a tube of insulation surrounding the encasement and snugly engaging the larger end of said encasement, whereby to support the tube from the upper terminal section and to permit unobstructed movement of the smaller end of the encasement from the tube when the encasement and wire 40 are severed.

45 5. A fuse link comprising an upper terminal section, a lower terminal section, a strain wire connecting said sections, and a low melting fuse section connecting the terminal sections, the ends of the fuse section being larger in diameter than the intermediate portion thereof; in combination with a tube of insulation surrounding the strain wire and fuse section and snugly engaging one of said ends of the fuse section. 5

6. A fuse link comprising an upper terminal section, a lower terminal section, a strain wire connecting said sections, and a low melting fuse section connecting the terminal sections, the ends of the fuse section being larger in diameter than the intermediate portion thereof and the end connected with the upper terminal section being larger in diameter than the other end; in combination with a tube of insulation surrounding the wire and fuse section and snugly engaging the larger of said ends. 6

7. A fuse link comprising a terminal section, a flexible section, a strain wire connecting said sections, and a low melting-conducting encasement surrounding the strain wire and connecting said sections, the ends of the encasement being larger in diameter than the intermediate portion thereof and the end connected with the terminal section being larger in diameter than the other end; in combination with a tube of insula- 7

tion snugly engaging the larger of said ends and extending therefrom to enclose said encasement and a portion of said flexible section.

8. A fuse link comprising a terminal section having a transverse aperture, a flexible section having a rigid portion provided with a transverse aperture, a strain wire having its ends looped through said apertures and twisted about an intermediate portion of the wire, and a low melting conducting encasement surrounding the wire and connecting said sections, the ends of the encasement being larger in diameter than the intermediate portion thereof and embedding the looped and twisted ends of said wire, the end connected with the terminal section being larger in diameter than the other end; in combination with a tube of insulation snugly engaging the larger of said ends and surrounding said encasement and a portion of the flexible section.

20 9. A fuse link comprising a terminal section

having an aperture, a flexible section having a rigid portion provided with an aperture, a strain wire having its ends looped through said apertures and twisted about an intermediate portion of the wire, and a low melting fusible portion connecting said sections, the ends of the fusible portion being larger in cross-sectional area than the intermediate portion thereof and embedding the looped and twisted ends of said wire. 5

10. A fuse link comprising a relatively rigid terminal section, a flexible terminal section in spaced relation to the rigid terminal section, a strain wire electrically connecting said sections and secured in direct electrical contact therewith, and a low-melting metallic sheath embedding 15 said strain wire and adjacent ends of said sections, whereby destructive torsional and bending stresses between said sections are minimized.
